UNITED STATES PATENT OFFICE.

WALTER M. SCOTT AND RALEIGH E. TRESISE, OF CLEVELAND, OHIO, ASSIGNORS TO THE STERLING MANUFACTURING COMPANY, OF CLEVELAND, OHIO, A CORPORATION OF OHIO.

BATTERY-METER.

1,199,829.

Specification of Letters Patent.

Patented Oct. 3, 1916.

Application filed November 6, 1914. Serial No. 870,548.

To all whom it may concern:

Be it known that we, WALTER M. SCOTT and RALEIGH E. TRESISE, citizens of the United States, residing at Cleveland, in the 5 county of Cuyahoga and State of Ohio, have invented new and useful Improvements in Battery-Meters, of which the following is a specification.

Our invention relates to meters, and particularly to meters of the permanent magnet type which are of a convenient compact construction adapting them to be applied to the dash boards of vehicles, to switch boards, and also which can be conveniently 15 made of a size enabling them to be carried in the pocket when used for testing batteries, either dry or storage cells.

Our invention has for its general object to simplify the construction and economize 20 the production of the frames upon which the operating parts or working elements of such meters are mounted, as well as to facilitate the assembling of such working parts. We realize such object by constructing 25 the frame in such manner that certain of the spacing and supporting devices—and preferably all of them—are made integral with the frame. By so constructing the frame, we have obviated a number of the 30 operations heretofore considered necessary to the production of the spacing and supporting means and to the assembling of the working elements, such production and assembling heretofore involving the production 35 of a plurality of separate members; and our invention has resulted in producing the meters, not only in a more economical manner, but in providing a more compact and reliable construction.

40 The annexed drawing and the following description represent means illustrating one type of our invention, such disclosed type representing, however, but one of the possible ways in which the spirit of our invention 45 may be utilized.

In said annexed drawing: Figure 1 represents a front elevation of an assembled meter of the volt-ammeter type embodying our invention; Fig. 2 represents a rear elevation 50 of a meter of the ammeter or volt-meter type, also embodying our invention, the rear of the case being removed; Fig. 3 represents a front elevation of our improved frame as it would appear if flattened out, showing in

dotted lines the cuts or incisions that are 55 made in the blank from which it is formed to provide the elements from which the several members embodied in the frame are formed up; and Fig. 4 shows a perspective view of the formed up frame, there being 60 shown therein the location of the indicator-pointer with reference to the coil-supporting member.

Referring to the annexed drawing, 1 represents the case of our improved battery 65 meter provided with the binding post 2 and the terminal 3. The meter is provided with a flexible copper wire cable 4 shown in Figs. 1 and 2. The peripheral wall of the case 1 is punched to provide small lugs 5 and 6 70 adapted to assist in retaining the integral frame 8, hereinafter referred to, securely in the casing 1; as, also, prevent the rear of the case being shoved too far into said wall. The permanent control of the meter, or the 75 element which exerts the permanent directive influence upon the same, is a magnet 7.

The integral, one-piece frame, shown at 8, is adapted to be a general supporting member for all the working elements of the 80 meter and to form in connection with a coil, hereinafter mentioned, an electrical connection between the binding post 2 and the terminal 3. This entire frame 8 is formed up from a one-piece blank in operations very few in number compared with 85 the operations heretofore necessary in making frames for a similar purpose from a plurality of blanks. The frame 8 is formed with a supporting ear 9 for securing 90 the frame within the case 1 as shown in Fig. 2, while a magnet support 10 and two supporting feet or spacing lugs 11 are formed up in the upper portion of the frame 8.

A coil-supporting and retaining member 95 12 and two supports 13 and 14, adapted to provide a pivotal support for an indicator pointer 15, are formed up in the lower portion of the frame 8. The coil-supporting member 12 is shown as a spool, but the two 100 members 16 and 17, Fig. 3, could be much shorter thus providing a coil-supporting portion which would be practically flat instead of a spool formation. The indicator pointer 15 plays through the spool 12, as 105 shown in Fig. 4, and has an armature portion 18, as shown in Figs. 2 and 4.

A cable 19 forming electrical connection

between frame 8 and the terminal 3 is wound into a coil 20 around the spool 12, and connected to frame 8 at 21 and to terminal 3 at 22 as shown. This cable 19 is 5 insulated from case 1 by means of the insulators 23. A dial is shown at 24 carried upon frame 8. A glass wall is provided, a small part of which is exposed as shown at 25.

10 Our improved meter can be used either as an ammeter, a volt-meter or both, and we wish particularly to lay stress upon the fact that the whole supporting frame of the instrument is formed up economically, 15 into a very strong and compact light-weight construction, and in its preferred embodiment from a one-piece blank which is absolutely integral.

Having thus described our invention, what 20 we claim is:

1. In a battery meter, a formed-up integral frame comprising a substantially semi-circular upper portion adapted to support the element which exerts permanent directive influence upon the meter, and an irregularly shaped lower portion formed into a spool.

2. A formed-up integral frame for the purposes described, comprising a portion 30 adapted to form a magnet support and a portion about which a coil may be wound, said latter portion adapted also to form a pointer support.

3. A formed-up integral frame for the 35 purposes described, comprising an upper portion formed up to carry a magnet and a lower portion formed up to provide a spool and to carry a pointer.

4. A formed-up integral frame for the 40 purposes described, comprising a supporting ear, a magnet-supporting portion, a spool, and pointer-supporting means.

5. A formed-up integral frame for the 45 purposes described comprising a portion adapted to carry a magnet and provided with a supporting ear and a portion forming a spool and provided with lugs formed up into pointer-supporting means.

6. In a battery meter, a case; a frame 50 secured therein; and operating elements including a pointer; a part of said frame being formed into a spool and a pointer support, said frame being further formed to carry all of the operating elements directly 55 upon itself.

7. In a battery meter, a case; a frame 60 secured therein; a dial; a coil; a magnet; and a pointer; said frame being of one-piece construction and adapted to support directly 65 upon itself said dial, coil, magnet and pointer, a portion of said frame being formed up into a spool about which said coil may be wound.

8. In a battery meter, a case; a frame 70 secured therein; a dial; a coil; a magnet; and

a pointer; said frame being of one-piece construction and adapted to support said dial, coil, magnet and pointer, and said pointer being so mounted as to play within the coil-supporting portion of said frame. 70

9. A formed-up integral frame for the purposes described, comprising a portion adapted to support the element which exerts permanent directive influence upon the meter and a portion adapted to form a coil-support and a pointer-support, said coil-support and said pointer-support being so relatively disposed as to allow the pointer to play within the coil-support. 75

10. An integral frame for the purposes 80 described, comprising upper and lower portions, said upper portion being formed with a supporting lug and supporting feet for the frame itself and with a supporting lug for a magnet, said lower portion being 85 formed into a spool and a pointer support.

11. An integral frame for the purposes described, comprising upper and lower portions, said frame being formed with two supporting lugs upon its upper portion, one 90 for the frame itself, and one for a magnet, the lower portion being bent to form a spool, and two lugs formed up from said lower portion and adapted to form a pointer support. 95

12. An integral frame for the purposes described, comprising a semi-circular portion and an irregularly shaped portion; said frame being formed with a peripheral lug upon said semi-circular portion, and a lug 100 struck up from the body of the latter; part of said irregularly shaped portion being bent forwardly to form a spool; and a rearwardly extending lug and a forwardly extending lug, formed up from this irregularly shaped portion, said last-mentioned two lugs being disposed in parallel planes. 105

13. In an electrical measuring instrument, a frame, a casing therefor, said frame being secured to the wall of the casing, means for 110 spacing the frame from the casing, a portion of the frame being formed to provide a spool, a deflecting coil carried by the spool, integral spacing arms secured to said spool, a pointer or needle arranged to extend through said spool and through the coil, and a pivot pin for said needle having pivotal bearings in said arms. 115

14. In a measuring instrument, a casing, a frame having a flanged portion arranged 120 to engage the interior wall of the casing, means for securing the frame to the casing, said frame having portions formed from the main body portion and spaced therefrom to provide a spool and being provided with 125 a portion formed to provide an offset supporting surface parallel with the plane of the main body portion, a coil of wire carried by said spool, and a permanent magnet carried by said offset portion, the poles of said 130

magnet being adjacent to one end of said spool.

15. In a measuring instrument, a casing, a frame having a flanged portion arranged to engage the interior wall of the casing, means for securing the frame to the casing, said frame having portions formed from the main body portion and spaced therefrom to provide a spool and being provided 10 with a portion forming an offset supporting surface parallel with the plane of the main body portion, a coil of wire carried by said spool, a permanent magnet carried by said offset portion, the poles of said magnet being adjacent to one end of said spool, and means for permitting adjustment of the magnet on its support.

16. An electrical measuring instrument comprising a casing, and a frame having 20 formed therewith spacing lugs adapted to space the frame from the front of the casing and also having formed therewith a lug whereby it may be attached to said casing, there being a spool carried by said frame

and having projections providing means for 25 supporting a pointer staff.

17. An electrical measuring instrument comprising a casing, a frame having formed therewith an attaching lug whereby it may be secured to the casing and a magnet supporting lug or projection, and a spool carried by the frame and having two opposed supports providing pivot bearings for the pointer staff.

18. A frame for instruments of the character described having formed therewith an attaching lug, a magnet supporting lug, and an integral spool, said frame having a pair of projections for pivotally supporting a pointer staff.

In testimony whereof, we have subscribed to this specification this 31st day of October, 1914.
